UNITED STATES PATENT OFFICE.

LEE S. CHADWICK, OF CLEVELAND, OHIO.

OIL-BURNER.

1,122,856.

Specification of Letters Patent.

Patented Dec. 29, 1914.

Application filed October 25, 1913. Serial No. 797,215.

To all whom it may concern:

Be it known that I, LEE S. CHADWICK, a citizen of the United States, residing at Cleveland, in the county of Cuyahoga and State of Ohio, have invented a certain new and useful Improvement in Oil-Burners, of which the following is a full, clear, and exact description, reference being had to the accompanying drawings.

This invention relates to oil burners, and has for its object to provide such burners with means whereby the wick may be raised and lowered within predetermined limits and, more particularly, to provide the wick raiser with an indicator which is capable of showing at all times the exact height of the wick and which is provided with means whereby it may be adjusted, as occasion may require, to compensate for the consumption and cleaning of the wick.

Among the objects of the invention are the production of a device of this kind which shall have the capabilities of operation referred to hereinbefore; which shall be simple of construction and convenient of operation; and generally responsive to all requirements and incidents of use.

Further objects of the invention will appear hereinafter and may be defined generally as consisting of the combinations of elements embodied in the claims hereto annexed and illustrated in the drawings accompanying and forming part hereof, wherein—

Figure 1 represents a view, partly in section and partly in elevation, of a burner having my invention applied thereto; Fig. 2 is an elevation, with parts broken away, of the burner and raiser shown in the preceding figure; Fig. 3 is a detail in section and elevation of the wick raiser and the associated parts; Fig. 4 a bottom plan view of a portion of the wick raiser; Fig. 5 a side elevation and Fig. 6 a sectional front elevation of a modified form of the invention.

Describing by reference characters the various parts shown herein, 1 denotes the inner and 2 the outer wick tube of a burner of any approved construction. Between these tubes there is shown a wick 3, the wick being provided with a carrier 4, said carrier being formed of perforated sheet metal.

5 denotes the spindle of the wick raiser, said spindle being provided with a double star wheel 6, which engages the perfora-

tions of the wick carrier. The spindle 5 is provided at its outer end with an operating handle 6^a, rigid therewith, said operating handle being in the form of a hand wheel which may be conveniently formed of sheet metal having a flange or skirt 7 extending toward the lower end of the spindle 5 and being substantially parallel with said spindle. The bottom of this flange or skirt 7 is provided with teeth or serrations 8, for a purpose to be described hereinafter. The spindle 5 is mounted within a sleeve 9, which extends through the housing 10, a supporting lug 11 and a plate 12, said lug and plate being soldered to the outer wick tube, the latter being provided with an extension 13 for facility of application to the said wick tube.

The plate 12, as will be more evident from Fig. 1, is provided with a segmental scale 14 which is adapted to coöperate with an indicating finger carried by and movable with the spindle 5. The scale 14 is provided with the word "Clean" at the central portion thereof, the word "Out" at one end thereof, and the word "Up" or "Full" may be provided at the opposite end; although a stop 15, which limits the rotation of the spindle in a wick-raising direction, enables the legend at this end of the scale to be dispensed with.

The indicating finger is conveniently and cheaply formed as one branch of a U-shaped sheet metal strap, the said strap being mounted on the sleeve 9 and the sleeve extending through both branches thereof. The indicating finger, shown at 16, is provided with a pin 17 which projects toward the plate 12, and the other end 16^a of this finger swings above the scale 14. The other branch 18 of the U-shaped strap has its end bent upwardly, as shown at 19, and is provided there with serrations or teeth adapted to mesh with the serrations 8 on the operating handle 6^a. A spring 20, surrounding the sleeve 9 and bearing against the plate 12 and the branch 16, normally maintains a driving connection between the spindle 5 and the indicating finger 16, through the engagement of the serrations 18 of the strap with the serrations on the hand wheel.

It will be noted that, in radial line with the center of the scale 14 and in line with the word "Clean", the plate 12 is provided with a hole 12^a.

In Fig. 5 there is shown a modification of my invention wherein the finger 16^a of the U-shaped strap is provided at its outer extremity with a stop lug 21, which is conveniently formed by bending the outer extremity of the finger substantially at right angles to the body thereof. This stop lug co-operates with a notch 22 in the curved periphery of the plate 12^b as well as with the projection 15^a.

As in the preceding embodiment of my invention, the driving connection between the spindle and the finger is secured by means of the spring 20^a which normally holds the serrations in the flange 19 in engagement with the serrations on the operating handle 6^a.

With the parts constructed as described, the operation will be as follows: The plates 20 12, 12^a and the segmental scale thereon will be so arranged and proportioned with reference to the wick spindle that, when the finger 16, 16^a is at the center of the scale, above the word "Clean", the top of the wick 25 will be substantially flush with the tops of the wick tubes. In this position, the wick may be cleaned by rubbing the top thereof with a cloth or other suitable object. The parts will be so proportioned further that, 30 when the pin 17, 21 is in engagement with the stop 15, 15^a, the wick will be at full height and, in the form of burner shown herein, this full height will be with the wick 35 slightly below the spreader plate 23.

As the wick necessarily becomes shortened, through its continued operation, some means for adjustment between the finger 16, 16^a and the wick spindle 15 must be provided. This adjustment is accomplished by rotating 40 the spindle until the pin 17, 21 comes in line with the hole 12^a, 12^b. It will be observed that ordinarily the pin or projection (17, 21) is in such close proximity to the co-operating plate therebeneath that insufficient room is provided to permit the disengagement of the U-shaped strap from the serrations in the hand wheel. This disengagement can be accomplished only when 45 the pin or projection (17, 21) is above the corresponding hole 12^a, 22 in the plate, or when the finger has been moved entirely off the plate in the "out" direction. It will be observed further that no such adjustment can be made when the finger is at the full height 50 position, since the pin or projection (17, 21) is engaged by the stop 15, 15^a. Ordinarily, however, the adjustment will be effected only when the pin or projection is above the hole near the middle of the plate opposite 55 the word "Clean." When in this position, the operator can press downwardly upon the finger 16, 16^a, the pin or projection then passing through the hole 12^a, 22, thereby disengaging the serrations in the flange 19 60 from those in the hand wheel 6^a. The spin-

dle can then be rotated until the top of the wick is brought flush with the top of the wick tubes, whereupon the pressure upon the finger 16, 16^a can be relieved and the indicating finger will again be locked to the 70 wick spindle.

Among the advantages of this invention are the fact that the stop 15, 15^a, in conjunction with the indicating finger, provides means whereby it will be impossible to turn 75 the wick too high, thereby securing proper functioning of the wick. Furthermore it will be apparent that a change of adjustment can be made only when the wick is turned to "clean" or extreme "out" position, with the top of the wick either substantially flush with the tops of the wick tubes or at a considerable distance below the tops of said tube. Still further, as will be plainly apparent, the construction is 80 extremely simple and economical of production and is clearly efficient in operation.

Having thus described my invention, what I claim is:—

1. In an oil burner, the combination of a 90 wick, a spindle for raising and lowering the same, a sleeve for said spindle, a plate through which said sleeve and spindle extend, a finger rotatably mounted on said sleeve, a hand wheel for the spindle, and an 95 adjustable connection between the hand wheel and the finger.

2. In an oil burner, the combination of a 100 wick, a spindle for raising and lowering the same, a sleeve for said spindle, a finger rotatably mounted on said sleeve, a hand wheel for the spindle, and an adjustable connection between the hand wheel and the finger.

3. In an oil burner, the combination of a 105 wick, a wick-raising spindle, a plate through which said spindle extends, said plate being provided with an aperture, a finger through which said spindle extends, said finger having a projection directed toward the plate 110 and adapted to enter the aperture thereof, a spring forcing the finger away from the plate, a handle for rotating the spindle, and an adjustable connection between the finger and the hand wheel.

4. In an oil burner, the combination of a 120 wick, a wick raising spindle, a plate provided with an aperture, within which the spindle is free to rotate, a finger having a projection directed toward the plate and adapted to enter the aperture, a spring which normally acts to hold the finger away from the plate, and an adjustable connection between the finger and the spindle.

5. In an oil burner, the combination of a 125 wick, a spindle for raising and lowering the same, a segmental plate provided with an aperture at substantially the central portion thereof and with a stop at one end thereof, a finger through which the spindle extends,

5 said finger having a projection extending toward the plate and adapted to enter the aperture and to engage the stop, a hand wheel having serrations on the under surface thereof, and a spring tending to force the finger toward the hand wheel, said finger having serrations adapted to engage the hand-wheel serrations.

6. In an oil burner, the combination of a wick, a spindle for raising and lowering the same, a segmental plate provided with an aperture at substantially the central portion thereof and with a stop at one end thereof, a finger through which the spindle extends, 10 said finger having a projection directed toward the plate and adapted to enter the aperture and to engage the stop, a hand wheel, a spring tending to force the finger toward the hand wheel and into engagement therewith, and means whereby the engagement between the hand wheel and the finger may be angularly varied.

7. In an oil burner, the combination of a wick, a wick-raising spindle, a plate having 25 an aperture therethrough, a substantially U-shaped strap surrounding said spindle, said strap having a branch constructed as a finger and said finger being provided with a projection adapted to enter the aperture 30 in the plate, the opposite branch of the said strap having an outwardly projecting flange provided with serrations, a hand wheel on the spindle, said hand wheel having serrations in the lower surface thereof, and a 35 spring surrounding the spindle and forcing the strap toward the hand wheel and normally maintaining the serrations in the said strap in mesh with the serrations in the hand wheel.

40 8. In an oil burner, the combination of a wick, a wick-raising spindle, a plate having a scale thereon and having an aperture at the central portion of the scale, a substantially U-shaped strap surrounding said 45 spindle, said strap having a branch constructed as a finger coöperating with the scale and said finger being provided with a projection adapted to enter the aperture in the plate, the opposite branch of the said 50 strap having an upwardly projecting flange provided with serrations, a hand wheel on the spindle, said hand wheel having serra-

tions in the lower surface thereof, a spring surrounding the spindle and forcing the strap toward the hand wheel and normally 55 maintaining the serrations in the said strap in mesh with the serrations in the hand wheel, and a stop carried by the plate and adapted to be engaged by the pin to limit the height of the wick.

60 9. In mechanism of the character described, the combination of a wick, a spindle for raising and lowering said wick, a stop device associated with the spindle, means adjustably connecting said device to said 65 spindle, and means coöperating with the stop device and preventing the disengagement of said device from the spindle except when the said device is in a predetermined position.

70 10. In mechanism of the character described, the combination of a wick, a spindle for raising and lowering said wick, a stop device, means including a spring for adjustably connecting the said device to the spindle, and means arranged to block the movement of the said device in the direction to disengage the same from the spindle except when the said device is in a predetermined position.

75 11. In mechanism of the character described, the combination of a wick, a spindle for raising and lowering the same, a plate, a finger longitudinally movable along said spindle and arranged on one side of said 80 plate, means including a spring for pressing the finger away from the plate and into locking engagement with the spindle, the said finger being provided with a projection extending toward the plate and in substantial engagement therewith when the finger is locked to the spindle, said plate having an aperture for the reception of the finger whereby the said finger may be moved against the action of the spring out of locking engagement with the spindle when in a 85 predetermined position with reference to the plate.

90 95 In testimony whereof, I hereunto affix my signature in the presence of two witnesses. 100
